UNITED STATES PATENT OFFICE.

WARREN S. BELLOW, OF EAST ORANGE, NEW JERSEY, ASSIGNOR TO WALDEN-WORCESTER, INC., OF WORCESTER, MASSACHUSETTS, A CORPORATION OF MASSACHUSETTS.

WRENCH CONSTRUCTION.

Application filed November 13, 1924. Serial No. 749,619.

To all whom it may concern:

Be it known that I, WARREN S. BELLOW, a citizen of the United States, resident of East Orange, county of Essex, and State of 5 New Jersey, have invented certain new and useful Improvements in Wrench Constructions, of which the following is a specification.

This invention relates to an improvement 10 in socket wrenches and other tools and more especially to an improvement in means for securing the sockets of such a wrench on the handle thereof.

In the securing of a socket or other tool 15 on the handle of a wrench of the types illustrated in the accompanying drawings it is necessary that the socket be retained against both longitudinal and rotational movement on the handle, and in the past it 20 has been customary to screw, rivet or pin the handle and socket together, providing in each instance a means to hold the socket against both longitudinal and rotational movement, in some instances providing one 25 means to hold against rotational movement and another means to hold against longitudinal movement.

In my copending application Serial No. 348,691 filed December 31, 1919, I have 30 shown and claimed a means for securing the socket on the handle of a wrench which comprises inserting the handle in a hole in the base of the socket and securing the two together by driving a portion of the socket 35 member from within the nut engaging socket into engagement with the handle to hold the socket against both longitudinal and rotational movement on the handle, this being the preferred embodiment of my 40 invention at the date of filing of said application because the displaced portion of the socket is partially concealed from view when located in the nut engaging socket.

As explained in said original application, 45 however, the displaced portion of the socket need not be located within the nut engaging portion thereof, and in some instances cannot be conveniently located therein.

It is therefore one of the objects of the 50 present invention to provide a wrench with the socket and handle secured together by driving an axially located portion of the socket into engagement with the handle

from a point outside the nut engaging portion of the socket.

A more specific object of the invention 55 is to apply this type of securing means to wrenches of the type wherein it is difficult or impractical to have the displaced portion inside the nut engaging portion of the 60 socket.

Other objects and advantages will appear as the description of the invention proceeds.

In the accompanying drawings I have 65 illustrated the invention as applied to wrenches of the type wherein it is difficult or impractical to locate the displaced portion of the socket inside the nut engaging portion thereof. It will be understood however that the means which I propose may 70 be applied if desired to socket wrenches of the type shown in my copending application above identified.

Figure 1 of the drawing is a part sectional view of one form of wrench, with 75 my invention applied thereto;

Fig. 2 is a part sectional view of another form of wrench;

Fig. 3 is a sectional view on the line 3-3 of Fig. 2;

Fig. 4 shows the invention applied to a 80 different type of tool; and

Fig. 5 is a view of another application of the invention.

In the embodiment shown in Fig. 1, the 85 socket 1 comprises an elongated body portion 2 having a nut engaging socket 3 in one end thereof and a handle receiving hole 4 near the other end, with the axis of the hole crossing the axis of the nut engaging 90 socket, and with a large body of solid metal between the bottom of the nut socket 3 and hole 4. A handle 5 comprising a bar or rod is inserted in the hole 4 and secured against longitudinal or rotational movement relative to the socket by driving a substantially axially located portion 6 of the 95 socket into engagement with the handle.

Figs. 2 and 3 show a different application of the invention wherein a short socket 7 100 has the nut engaging portion 8 extend as far into the socket as possible to provide a deep nut engaging portion. The hole 9 for the handle extends through the base of the socket at right angles to the nut engaging portion and the handle 10 may project as at 105

into the upper end of the nut engaging portion making it substantially impossible to secure the socket on the handle by displacing a portion from within the nut engaging socket. In this embodiment of the invention therefore the portion 6^a at the top or base of the socket is indented to drive the metal of the socket against and into the handle 10 to secure the socket against longitudinal and 10 rotational movement on the handle.

Fig. 4 shows the invention applied to the T shank of a wrench or other tool. In this embodiment the shank 11 may be provided with an enlarged head 12 through 15 which the handle receiving hole 13 passes at right angles to the shank. A handle 14 is passed through the hole 13 and secured against longitudinal or rotational movement relative to the shank by an axially located 20 portion 6^b of the head 12 driven into engagement with the handle. The lower end 11^a of the shank may be squared to fit into a socket or other tool for turning the same.

Fig. 5 shows a wrench 15 of comparatively 25 small size similar to the wrenches shown in my copending application above identified, in which the nut engaging portion 16 is of such a small diameter as to preclude a punch of sufficient size to withstand the driving 30 strain thereon being inserted therein. In this application of the invention it is therefore desirable to use a larger size punch and drive a portion 6^c from the top or base of the socket into engagement with the handle 35 17 to hold the socket against longitudinal or rotational movement on the handle.

I have illustrated various applications of my invention in the accompanying drawings which are to be taken solely by way of il-

lustration and not by way of limitation as 40 various other applications of my invention can be made without departing from the spirit of the invention or the scope of the appended claims.

I claim:

1. In a socket wrench, the combination of 45 a socket member having therein a nut-engaging socket and a handle-receiving hole, said handle-receiving hole being located within the base portion of the socket member with the axis of said hole crossing the axis of the nut-engaging socket, and a handle inserted in said hole and held against longitudinal and rotational movement therein by an integral axially located portion of 50 the socket member driven into engagement with said handle from outside the nut-engaging socket.

2. In a tool of the type described, a turning member and a turned member, means 60 at one end of the turned member to cooperate with a part to be turned, and means at the other end of the turned member for securing the turned member and the turning member together comprising a hole in 65 the turned member into which the turning member is inserted, and means to prevent longitudinal and rotational movement of one of said members relative to the other, comprising an integral axially located portion of 70 the turned member driven into engagement with the turning member from the end opposite the means to cooperate with the part to be turned.

In testimony whereof I have affixed my 75 signature to this specification.

WARREN S. BELLows.
